UNITED STATES PATENT OFFICE

HAROLD PAUL SMITH, OF RED BANK, NEW JERSEY

DESIGN FOR A LIGHTING UNIT

Application filed June 9, 1931. Serial No. 40,135. Term of patent 14 years.

To all whom it may concern:

Be it known that I, HAROLD P. SMITH, a citizen of the United States, residing at Red Bank, in the county of Monmouth and State of New Jersey, have invented a new, original, and ornamental Design for a Lighting Unit, of which the following is a specification, reference being had to the accompanying drawings, forming part thereof.

Figure 1 is a perspective view of a lighting unit, Figure 2 is a top plan view of the same, and Figure 3 is a bottom plan view.

I claim:

The ornamental design for a lighting unit as shown.

HAROLD PAUL SMITH.
